METHOD AND MACHINE FOR SHAPING THE BOTTOMS OF SHOES

Fount E. Curtis, Milwaukee, Wis., assignor to
United Shoe Machinery Corporation, Borough
of Flemington, N. J., a corporation of New
Jersey

Application November 13, 1939, Serial No. 304,000

6 Claims. (Cl. 12—34)

This invention relates to the shaping of the bottoms of shoes and is illustrated herein in its application to the shaping or leveling of the bottoms of shoes of the type provided with out-soles made of comparatively soft material, although it will be understood that the invention, in its more general aspects, is not thus limited in utility, but is applicable to the manufacture of shoes of various kinds.

10 In the manufacture of shoes of the above-mentioned type it has sometimes proved to be difficult to produce as even and smooth a bottom surface as desired in a leveling operation, particularly when the leveling pressure is applied progressively, which is the frequent practice. In applying the leveling pressure progressively to different portions of the sole by means of the usual roll, it has been found that there is a tendency for the material of the sole 15 to creep under the action of the roll with the result that an objectionable wavy appearance is produced in the sole. While more satisfactory results may be obtained by the use of a molded saddle applied tightly to the bottom of the shoe 20 for transmitting the pressure of the roll to the sole, it has also been found that creeping of the material of the sole is not entirely avoided, since the pressure of the roll on the saddle sometimes tends to displace the saddle relatively to 25 the shoe.

The present invention, in one important aspect, provides a novel method whereby the desired shaping or leveling of the sole is effected by the use of a roll and an unmolded apron of 30 flexible material, preferably leather, interposed loosely between the roll and the shoe bottom. It has been found that the apron acts to transmit the shaping or leveling pressure to the sole with the desired uniformity and to modify the 35 action of the roll so as to avoid any tendency for the material of the sole to creep. For the practice of this method there may advantageously be utilized machines of the type used heretofore to apply leveling pressure progressively 40 to different portions of a shoe sole successively, the apron being interposed loosely between the roll and the shoe bottom for transmitting the pressure of the roll to the sole.

In another aspect the invention provides a 45 novel organization whereby the use of a flexible apron, such, for example, as above described interposed loosely between the leveling roll and the shoe bottom for transmitting the pressure of the leveling roll to the bottom of the shoe, is greatly facilitated. As herein illustrated, the

5 apron is connected at one end to the shoe-supporting jack with its other end free so that it may be draped over the leveling roll and thus maintained in an out-of-the-way position at the end of each leveling operation to avoid interference between it and different shoes as the 10 shoes are mounted on the jack and removed therefrom, the apron being applied loosely to the bottom of each shoe by the roll in response to the relative movement of the shoe-supporting 15 jack and the roll at the beginning of each leveling operation.

The invention will now be more particularly described by reference to the accompanying drawing and thereafter pointed out in the claims.

15 In the drawing,

Fig. 1 is a side elevation of a portion of a machine adapted for use in practicing the method of this invention and in which features of the 20 invention are embodied, and

Fig. 2 is a view similar to Fig. 1 but illustrating the relative positions of the apron and the leveling roll in applying pressure progressively to different portions of the shoe bottom.

25 Since the invention in its machine aspects is illustrated as applied to a leveling machine of a well-known type, only such parts of the machine as it is necessary to refer to for an understanding of the invention are shown and will be described in detail. Features of the general organization of machines of this type are described in various prior United States Letters Patent, including Letters Patent No. 1,667,761, granted on May 1, 1928, and No. 1,719,158, granted on July 2, 1929, both upon applications of 30 E. E. Winkley and H. A. Davenport. It will be understood that the machine includes an automatically controlled leveling roll 10 and a shoe support or jack which, in the power operation 35 of the machine, is moved automatically in directions lengthwise of the shoe to cause the roll to operate progressively along the bottom of the shoe. The jack comprises a toe post 12 and a heel post 14 which are pivoted together for relative adjustment for shoes of different sizes by 40 means of a threaded adjusting rod (not shown) which moves the heel post toward or from the toe post so that the toe ends of shoes of different sizes will be presented in substantially the same relation to the roll 10. The jack as a 45 whole is operatively movable about the axis of a shaft (not shown) on which the toe post is mounted, and power-operated means, not herein shown, is provided for imparting to the jack oscillatory movements about this axis to carry 50

the shoe rearwardly and forwardly under the leveling roll. The toe and heel posts are provided with means for supporting a shoe and last for the leveling operation. Mounted on the toe post 12 is a toe rest comprising a block 16 having secured to it a rubber pad 18 for engaging the toe end of the shoe. The heel post 14 supports a block 20 carrying a spindle 22 arranged to enter the spindle hole in the heel end 10 of the last. As shown, the block 20 is pivotally connected to the heel post for swinging movements about an axis extending laterally of the shoe to permit tipping movements to be imparted to the spindle in directions toward and 15 from the toe rest. The block 20 is connected by a link 24 to mechanism, not herein shown, whereby the block and spindle may be swung to press the toe end of the shoe firmly down upon the toe rest.

20 For purposes of this invention there is provided an unmolded apron 26 of flexible material, preferably leather, for transmitting the pressure of the leveling roll 10 progressively to different portions of the sole of a shoe on the shoe support. 25 The apron 26 is preferably of a size sufficient to cover the bottom of the largest shoe to be operated upon, and, as illustrated, is connected at one end by means of a plate 28 and screws 30 to an upwardly extending projection 32 on the toe post 30 12. This permits the operator to place the apron in a convenient out-of-the-way position at the end of each leveling operation by draping the apron over the leveling roll 10, thus avoiding any interference between the apron and different 35 shoes as they are mounted on the shoe support and removed therefrom. Moreover, it will be evident that with the apron thus supported, there is no need for the operator, after mounting a shoe on the shoe support, to apply the apron loosely 40 to the bottom of the shoe, since the apron is thus applied by the leveling roll in response to relative movement of the shoe support and the roll at the beginning of each leveling operation. In 45 the operation of the machine, as the shoe support is moved in directions lengthwise of the shoe relatively to the leveling roll 10, the apron 26 moves with the shoe support while extending loosely over the bottom of the shoe between the shoe and the leveling roll. Accordingly, the leveling 50 roll 10 rolls on the apron 26, and the pressure of the roll is transmitted through the apron progressively to different portions of the shoe sole 55 successively with the result that creeping of the material of the sole is avoided and the desired even and smooth bottom surface is produced.

While the invention is herein illustrated in its application to the manufacture of shoes the outsoles of which are made of comparatively soft material, it is not necessarily limited to use on shoes of that particular type, since it is contemplated that an apron such as that shown and described is likewise well adapted for use not only in applying sole-leveling pressure to shoes of various kinds but also in applying pressure to the bottoms of welt shoes prior to the applications of the outsoles to the shoes.

Having described the invention, what I claim as new and desire to secure by Letters Patent of the United States is:

1. That improvement in methods of shaping or leveling the bottoms of shoes which consists in applying loosely over the bottom of a shoe an unmolded apron of flexible material, and applying rolling pressure to said loosely applied apron 5 to shape or level different portions of the shoe bottom.

2. That improvement in methods of shaping or leveling the bottoms of shoes which consists in applying loosely over the bottom of a shoe an unmolded flexible leather apron, and while said apron is thus loosely applied operating through it to apply rolling pressure progressively to different portions of the forepart and shank of the shoe sole to level them. 10

3. In a machine for pressing the bottoms of shoes, a roll, a shoe support, said support and roll being relatively movable in directions lengthwise of a shoe on said support to cause the roll to operate progressively along the shoe bottom, 20 and a flexible apron connected at one end only to the shoe support and arranged to be interposed loosely between the leveling roll and the shoe bottom for transmitting the pressure of the roll to the bottom of the shoe. 25

4. A machine for shaping or leveling the bottoms of shoes having, in combination, a shoe support and a leveling roll relatively movable to level the forepart and shank of the sole of a shoe on said support, and an unmolded leather 30 apron connected at one end only to the shoe support, said apron being adapted to cover the bottom of the shoe and being arranged to be interposed loosely between the roll and the shoe bottom for transmitting the pressure of the roll 35 progressively to different portions of the forepart and shank successively in response to relative movement of the support and said roll.

5. In a leveling machine, the combination with a leveling roll and a shoe support comprising 40 a heel post and a toe post, said shoe support and leveling roll being relatively movable in directions lengthwise of a shoe on said support to cause the roll to operate progressively along the shoe bottom, of an unmolded apron of flexible 45 material arranged to extend loosely between the roll and the shoe bottom for transmitting the pressure of the roll successively to different portions of the bottom of the shoe, said apron being connected at one end to said toe post to permit it 50 to be draped over the roll in an out-of-the-way position at the end of each leveling operation.

6. In a leveling machine, the combination with a leveling roll and a shoe support relatively movable in directions lengthwise of a shoe on said 55 support to cause the roll to operate progressively along the bottom of the shoe, of an unmolded leather apron for transmitting the pressure of the roll successively to different portions of the shoe bottom, said apron being connected at one 60 end to said shoe support and free at its other end so that it may be draped over the leveling roll and applied loosely over the bottom of each shoe in response to the relative movement of the shoe support and the leveling roll. 65

FOUNT E. CURTIS.
